MOLD FOR NONFERROUS CASTINGS

Application filed May 23, 1931. Serial No. 539,426.

This invention relates to molds and more particularly to the art of casting non-ferrous metal compositions, such as piston packing rings, in which there is a relatively high lead or copper content. Heretofore, it has been proposed to cast such mixtures or alloys either in refractory molds, or in molds comprising metal parts associated with sand cores having gates and risers, or in split molds.

The object of the present invention is to provide a simple, inexpensive and permanent mold for the casting of such compositions, the mold being characterized by the absence of gates or risers and the use of metallic mold and core elements which define an open top cavity within which the casting is formed. The provision of an old metal open top mold dispenses with the usual assortment of molding apparatus for forming gates, risers and passages for the escape of gases and eliminates the waste of metal in cutting off sprues, thus reducing to a minimum the amount of metal poured for each casting. Furthermore, it is found that the castings formed in molds constructed in the manner of this invention are more homogeneous and have a denser grain structure.

A further object of this invention is to provide an open top metallic mold formed in one piece to substantially the shape of a tray whereby the mold may be conveniently supported on mold conveying apparatus in a position in which the casting composition may be readily poured, and with capacity for tilting while resting in place on the conveying apparatus, so that the mold need not be physically handled during the operation of discharging the casting therefrom.

Other objects and advantages characterizing our invention will become more fully apparent from the description which follows hereinafter and which has reference to one embodiment or example of the invention illustrated in the accompanying drawing, 45 whereof:

Fig. I represents a plan view of a mold and core constructed in the manner of our invention; and,

Fig. II represents a cross section of the same taken as indicated by the lines II—II 50 of Fig. I.

With reference to the drawing, it will be seen that the mold element 1 is substantially square having slightly curved sides 2 provided with two pairs of integral trunnions 3 disposed at a distance above the center of gravity and adapted to serve as pivotal supports by means of which the mold may be tiltably mounted on a conveying apparatus. Such a conveyor is described in our co-pending application for U. S. Letters Patent, Serial No. 539,427, filed May 23, 1931. The provision of a symmetrical mold with alternate pairs of trunnions enables the mold to be turned to different positions within its supporting apparatus, so that when one set of trunnions wears away a new set may be employed, and the life of the mold may thereby be substantially increased.

The body of the mold is in the general 70 shape of a tray and comprises an annular central portion 4, terminating at the top in an outwardly extending flange 5, and radial ribs 6 joining the bottom of the central portion 4 with the side edges of the flange 5. Adjacent to the central circular opening 13, the body of the mold is formed with an annular shoulder 7 affording an angular recess 8 upon which the cylindrical core 9 is seated. A sloping wall 10 on the inside of the mold leads upward and outward and merges with a vertical cylindrical wall 11 of a height corresponding substantially to the thickness of the flange 5. These walls 10 and 11 together with the outer wall of the cylindrical core 9 define an annular cavity which is filled by the casting composition 12 and which is open at its top.

Both the body of the mold 1 and the core element 9 are preferably made of cast iron. In the example shown in the drawing, the 90

core element 9 is interiorly hollowed and provided with a relatively thin wall. This permits the radiation of heat from the center of the mold to more effectively chill the cast metal 12.

An example of the composition or mixture which we preferably employ for the casting of piston packing rings is as follows:

	Per cent
Lead	31
10 Copper	65
Nickel	3
Sulphur	1

With such a composition or mixture we have found that the use of an open top metallic mold as herein described produces a homogeneous close-grained casting of a quality as good, if not superior, to castings produced in refractory molds. While we are aware that piston packings have been cast heretofore in molds having metal walls and metal cores, such molds have been combined with copies having gates or risers constituting a cumbersome assemblage of parts. By dispensing with such elements the operations of pouring and of discharging the castings are obviously simplified.

Furthermore, the provision of a one piece mold open at the top has obvious advantages over the use of split molds or molds made up of a multiplicity of elements hinged or otherwise assembled together. By seating the removable core 9 in the mold in the manner described, it will be noted that the casting 12 may be readily removed, with the operation consisting of tilting the mold about a pair of trunnions 3, allowing the casting to fall out, or permitting the casting to be tapped out by a blow with access to the underside of the core had through the opening 13.

While we have described and illustrated one example or embodiment of our invention, it will be apparent that various changes may be made in the form of the mold and core elements as herein described without departing from the spirit of our invention as defined in the claim hereto annexed.

Having thus described our invention, we claim:

A one piece metallic mold for casting non-ferrous rings of the character described, said mold having a central circular opening, and a removable core defining with said mold a cavity having a cylindrical open top, said core seating on an annular shoulder adjacent to said central circular opening in the body of said mold.

In testimony whereof, we have hereunto signed our names at Altoona, Pennsylvania, this 19th day of May, 1931.

VICTOR P. SCHMIDT.
HARRY A. BRENAMAN.
